UNITED STATES PATENT OFFICE.

WILLIAM J. CAMPBELL, OF INDIANAPOLIS, INDIANA.

ERASER ATTACHMENT FOR PENCILS.

1,353,215.

Specification of Letters Patent. Patented Sept. 21, 1920.

Application filed March 29, 1920. Serial No. 369,738.

To all whom it may concern:

Be it known that I, WILLIAM J. CAMPBELL, a citizen of the United States, residing at Indianapolis, in the county of Marion 5 and State of Indiana, have invented a new and useful Eraser Attachment for Pencils, of which the following is a specification.

The pencil now commonly known in the market as "Ever Sharp" is one comprising 10 a metallic barrel, adapted to contain a short section of lead and to present the same progressively for use as the same wears. This article is provided at its upper end with a removable cap which covers and protects a 15 short section of eraser which soon wears out and is not readily replaceable.

The object of my present invention is to 20 provide a neat and efficient attachment which may be readily applied to the upper end of a pencil of this kind and which will hold a short cylindrical section of eraser in such manner that it may be readily adjusted as it wears and readily replaceable 25 in the course of time.

While the device has been primarily designed for attachment to the so-called 30 "Ever Sharp" pencil, it will be readily understood that with slight modifications which will be apparent to any skilled 35 mechanician, the attachment may be applied to an ordinary wooden pencil, or pencils of other types.

The accompanying drawings illustrate 40 my invention. Figure 1 is a side elevation of an "Ever Sharp" pencil to which my device has been applied; Fig. 2 is an enlarged section of my device shown in position upon an "Ever Sharp" pencil; Fig. 3 a side elevation of the main body of my device; and Fig. 4 a plan of the part shown in Fig. 3.

My device comprises a main metal shell 10, having a threaded shank 11. The lower end of the shell is slit longitudinally at 45 various circumferentially spaced points, as indicated at 12, and this lower end is formed with an inturned gripping edge 13 and a shoulder 14, in the present instance being formed so as to grip the circumferential rib 15 found upon an "Ever Sharp" pencil, 50 the shoulder 14 lying squarely upon the upper end of the pencil, as shown in Fig. 2, so as to stabilize the body 10 upon the pencil body 16. The bore of the shell 10 is cylindrical and of a size to fit a cylindrical section 55 of eraser 17, eraser material of this form being readily procurable in the market.

Threaded upon threads 11 is a clamping

sleeve 18 provided at its lower end with a conical seat 19 adapted to coact with the conical flaring portion 20 of shell 10. 60

When the clamping sleeve 18 is unscrewed to some extent upon threads 11, the gripping fingers of shell 10, formed by the slits 12, may be snapped over the rib 15, whereupon the clamping sleeve 18 may be 65 screwed down so as to bring its tapered seat 19 against the tapered shoulder 20 of the gripping fingers and thus compress said fingers around the rib 15 and at the same time compress the fingers upon the lower 70 end of the eraser 17.

When the clamping sleeve 18 is slightly loosened on shell 10, the eraser 17 may be 75 axially adjusted to any desired point.

It will be readily seen that by proper 80 modification of the inner surfaces of the lower ends of the gripping fingers of shell 10, the device may be formed for engagement with the upper end of any desired form of pencil.

I claim—

1. As an article of manufacture, an eraser attachment for pencils, comprising a tubular body adapted to receive a section of eraser material, gripping fingers carried by 85 the lower end of said body and forming part of the eraser receiving bore, and a clamping sleeve threaded upon said body, the clamping sleeve and fingers having coacting surfaces by which the fingers may be contracted 90 upon the upper end of a pencil and upon the eraser material.

2. As an article of manufacture, an eraser attachment for pencils, comprising a tubular body longitudinally slotted at one end to 95 form gripping fingers, a clamping sleeve threaded on the tubular body, and interacting cam portions on the sleeve and fingers for contracting the fingers and the bore.

3. As an article of manufacture, an eraser attachment for pencils, comprising a tubular body longitudinally slotted at one end to form gripping fingers, a shouldered gripping groove formed in said fingers, a clamping sleeve threaded on the tubular body, and interacting cam portions on the sleeve and fingers for contracting the fingers and the bore.

In witness whereof, I have hereunto set 110 my hand at Indianapolis, Indiana, this 25th day of March, A. D. one thousand nine hundred and twenty.

WILLIAM J. CAMPBELL.
